GAME NET AND METHOD OF MAKING
THE SAMELothar A. Ederer, Chicago, Ill., assignor to R. J.
Ederer Company, Chicago, Ill., a corporation
of Illinois

Application November 10, 1948, Serial No. 59,358

12 Claims. (Cl. 273—29)

1

This invention relates to a net and to a method of making and finishing it. It has for one object to provide a tennis net in which a tape or fabric band is placed along one edge of the net and encloses the upper edge.

It has for another object to provide a method for making and finishing the edge of such a net.

A still further object is to provide a method of finishing and reinforcing one edge of a net without damaging or weakening the cords or threads of which the net is made.

Another object is to provide a net reinforced and finished along one edge to provide means for receiving a supporting rope or cord without damaging the threads or cords of which the net is made.

Other objects will appear from time to time in the course of the specification.

The invention is illustrated more or less diagrammatically in the accompanying drawing wherein:

Figure 1 is a plan view of a portion of one form of the net with parts broken away and parts omitted.

Figure 2 is a vertical section taken on an enlarged scale at line 2—2 of Figure 1.

Figure 3 is a plan view of one portion of the finishing or edging member.

Figure 4 is a side elevation illustrating the net when partially finished.

Like parts are indicated by like numbers throughout the specification and drawings.

In the particular form here shown, the net is formed of cords 1, 1 which are knotted or joined together as at 2, 2. When the net is to be finished, for example, when a portion of net is to be made into a tennis net or other game net, a piece of suitable size is prepared or cut from a larger piece. When this is done, free ends 3 of the cords extend above the uppermost longitudinal cord 4. The upper edge of a game net, and frequently the lower edge, must be reinforced and must be provided with finishing means. It is advisable, when this is done, to provide means for supporting the net from the finishing edge and from the material of which the finishing edge is formed. It is particularly advisable to accomplish this without stitching through any of the vertical threads below the uppermost horizontal thread 4. Such stitching, if present, is likely to damage and weaken the vertical cords. Hence, the present invention provides a convenient means for securing the finishing and edging material to a net without positioning any stitches below the uppermost horizontal net member or cord. The edge

finishing of the present invention may be applied to any edge of a net—an end edge, a top edge or a bottom edge. In the particular form shown herewith, the finishing is applied to the top edge but this does not indicate that the type of edge finishing shown herewith could not equally well be applied to another edge.

5 5 is a member which forms a part of the edge finishing structure. It is provided with a plurality of integral tabs or extensions. This member is shown in plan in Figure 3.

When the net is to be finished, a net portion of suitable size is prepared and a member, such as that shown in Figure 3, is also prepared. The 10 width of the tabs 6 is such that they may pass freely through the meshes of the net, and preferably, they are nearly as wide as the width of a mesh although they might be narrower.

In assembling the device, the parts are arranged as shown in Figure 4. Each tab 6 passes through one of the meshes 7 of the net. The tabs are then folded upwardly across the solid portion 5 and they are stitched to the solid portion by one or more rows of stitches 8, 8. From an 15 inspection of the figures, it is clear that the stitches 8 are all above or outside of the cord 4 and therefore the cords below or inside of this edge cord are not stitched and there is no danger of damage from the perforation by the needle or from the stitching.

20 After the net member has been constructed as shown in Figure 4, a finishing and loop holding section is added. The purpose of this is obvious and it affords a further reinforcement for the finished edge of the net. As shown in Figures 1 and 2, this reinforcing comprises an inner member 9 and an outer member 10. The outer member 10 has inturned edges 11 which engage and retain in place the lower edges of the inner member 9. After the finishing strap formed of the members 9 and 10 has been put in place, rows of stitches 12, 12 are put in place. These stitches pass through the member 5 and its integral tabs 6 but are all above the lower or outer 25 cord 4 of the net proper. The outermost member 10 may, if desired, be provided with waterproofing or preservative material, or both, and it may be of material stronger and stiffer than the inner member or they may be formed of identical material. The invention is not limited to the use of any particular materials in forming the finishing edge treatment.

30 When the net is complete, as shown in Figure 1, a rope or cable 13 is ordinarily inserted in the 35 cavity 14 formed within the members 9 and 10.

These members, as shown in Figure 2 in particular, form a cavity beyond the edge of the net and beyond the member 5, 6, and this cavity is suitable for the insertion of a supporting cord or cable upon which the net may be hung or by means of which the net may be held tight or otherwise held in suitable position if the finishing treatment is elsewhere than along the top of the net.

Although I have shown an operative form of my invention, it will be recognized that many changes in the form, shape and arrangement of parts can be made without departing from the spirit of the invention, and my showing is therefore to be taken as, in a sense, diagrammatic.

I claim:

1. In combination in a game net, a main net body formed of a plurality of flexible members arranged to form a plurality of meshes and means for finishing an edge of said net, said finishing means including a member provided with a plurality of laterally directed unitary parts, said parts extending through said meshes and being positioned against said member, and stitches holding said member and said parts together, said stitches being positioned outside of said main net body, and cavity forming means comprising a folded fabric member, the edges of said fabric member overlying said first-mentioned member and its parts, and stitches extending through said fabric members, said stitches being positioned outside of the main net body.

2. In combination in a game net, a main net body comprising a plurality of flexible cord-like members arranged to form a plurality of meshes and means for finishing an edge of said net, said finishing means including a member with a plurality of separated, laterally directed unitary parts, each of said parts extending through one of said meshes and being positioned against said member, and stitches holding said member and said parts together, said stitches being positioned outside of said main net body, and cavity forming means comprising a folded fabric member, the edges of said fabric member overlying said first-mentioned member and its parts, and stitches extending through said fabric members, said stitches being positioned outside of the main net body.

3. In combination in a game net, a main net body comprising a plurality of flexible cord-like members arranged to form a plurality of meshes and means for finishing an edge of said net, said finishing means including a unitary member having a plurality of separated, laterally directed unitary parts, each of said parts extending through one of said meshes, engaging one of said cord-like members and being positioned adjacent said unitary member, and stitches holding said member and said parts together, said stitches being positioned outside of said main net body, and cavity forming means comprising a folded fabric member, the edges of said fabric member overlying said first-mentioned member and its parts, and stitches extending through said fabric members, said stitches being positioned outside of the main net body.

4. In combination in a game net, a main net body formed of a plurality of flexible cord-like members arranged to form a plurality of meshes and means for finishing an edge of said net, said finishing means including a member having a plurality of separated unitary parts, said parts extending through said meshes and being positioned against said member and surrounding one

5 of said cord-like members adjacent an edge of said net, and a plurality of rows of stitches holding said member and said parts together, said stitches being positioned outside of said main net body, and cavity forming means comprising a folded fabric member, the edges of said fabric member overlying said first-mentioned member and its parts, and stitches extending through said fabric members, said stitches being positioned outside of the main net body.

5. In combination in a game net formed of a plurality of cords, said cords intersecting and being joined to form knots and meshes, and means for finishing and supporting said net, said means comprising an inner finishing member, a plurality of tabs integral with said member, each of said tabs being positioned through a mesh, said tabs engaging the uppermost cord of said net and stitches joining said member and said tabs, said stitches being positioned above the uppermost cord of said net, and an outer finishing member formed of folded material, the edges of said member overlying the net, terminating above the uppermost cord of said net, and stitches engaging said outer member and said inner finishing member, all said stitches being positioned above the uppermost cord of said net, said outer finishing member comprising a portion positioned and dimensioned to receive and enclose a net supporting member.

6. In combination in a game net formed of a plurality of cords, said cords intersecting and being joined to form knots and meshes, and means for finishing and supporting said net, said means comprising an inner finishing member, a plurality of tabs integral with said member, each of said tabs being positioned through a mesh, said tabs engaging the uppermost cord of said net and stitches joining said member and said tabs, said stitches being positioned above the uppermost cord of said net, and an outer finishing member formed of folded material, the edges of said member overlying the net, terminating above the uppermost cord of said net, and stitches engaging said outer member and said inner finishing member, all said stitches being positioned above the uppermost cord of said net, said outer finishing member comprising a portion positioned and dimensioned to receive and enclose a net supporting member.

7. In combination in a game net formed of a plurality of generally horizontal and generally vertical cords, said cords intersecting and being joined to form knots and meshes, and means for finishing and supporting said net, said means comprising an inner finishing member, a plurality of tabs integral with said member, each of said tabs being positioned through a mesh, said tabs engaging the uppermost horizontal cord of said net and stitches joining said member and said tabs, said stitches being positioned above the uppermost horizontal cord of said net, and an outer finishing member formed of a plurality of plies of folded material, the edges of said members overlying the net, terminating above the uppermost horizontal cord of said net, and stitches engaging said outer members and said inner finishing member, all said stitches being positioned above the uppermost horizontal cord of said net, said outer finishing member comprising a portion positioned and dimensioned to receive and enclose a net supporting member.

8. The method of finishing the edge of a net, which net is formed of cords knotted together to produce meshes, which method comprises the

following steps: preparing a net body of suitable size, preparing a longitudinally extended member and forming on said member a plurality of integral tabs, inserting each tab in an edge mesh of said net body and folding each tab about the edge net cord and against the said longitudinally extended member and securing said tabs to said member by stitches positioned outside the edge cord, thereafter folding a finishing member about the upper edge of said net, and securing the whole together by forming stitches above the uppermost net cord.

9. The method of finishing the edge of a net, which net is formed of cords knotted together to produce meshes, which method comprises the following steps: preparing a net body of suitable size, preparing a longitudinally extended member and forming on said member a plurality of integral tabs, inserting each tab in an edge mesh of said net body and folding each tab about the edge net cord and against the said longitudinally extended member and securing said tabs to said member by stitches positioned outside the edge cord, thereafter folding a finishing member about the upper edge of said net, and securing the whole together by forming a plurality of rows of stitches through the respective parts and above the uppermost net cord.

10. The method of finishing the edge of a net, which net is formed of cords knotted together to produce meshes, which method comprises the following steps: preparing a net body of suitable size, preparing a longitudinally extended member and forming on said member a plurality of integral tabs, inserting each tab in an edge mesh of said net body and folding each tab about the edge net cord and against the said longitudinally extended member and securing said tabs to said member by stitches positioned outside the edge cord, thereafter folding a finishing member about the upper edge of said net and about said longitudinal member and its tabs, and securing the whole together by forming stitches above the uppermost net cord.

11. The method of finishing the edge of a net, which net is formed of cords knotted together to produce meshes, which method comprises the following steps: preparing a net body of suitable size, preparing a longitudinally extended member and forming on said member a plurality of integral tabs, inserting each tab in an edge mesh of said net body and folding each tab about the edge net cord and against the said longitudinally extended member and securing said tabs to said member by stitches positioned outside the edge cord, thereafter folding a finishing member about the upper edge of said net and about said longitudinal member and its tabs, and securing the whole together by forming stitches through the respective parts and above the uppermost net cord.

12. The method of finishing the edge of a net, which net is formed of cords knotted together to produce meshes, which method comprises the following steps: preparing a net body of suitable size, preparing a longitudinally extended member and forming on one side of said member a plurality of integral tabs, inserting each tab in an edge mesh of said net body and folding each tab about the edge net cord and against the said longitudinally extended member and securing said tabs to said member by rows of stitches positioned outside the edge cord, thereafter folding a multi-ply outside finishing member about the upper edge of said net and about said longitudinal member and its tabs, and securing the whole together by forming a plurality of rows of stitches through the respective parts and above the uppermost net cord.
